UNITED STATES PATENT OFFICE

ERNST SACHS, OF GOEGGINGEN, NEAR AUGSBURG, GERMANY, ASSIGNOR OF ONE-HALF TO MASCHINENFABRIK AUGSBURG-NUERNBERG, AKTIENGESELLSCHAFT, OF AUGSBURG, GERMANY, AND ONE-HALF TO ASBERN MASCHINENFABRIK-AKTIENGESELLSCHAFT, AUGSBURG-GOEGGINGEN, OF GOEGGINGEN, NEAR AUGSBURG, GERMANY

FORM CYLINDER FOR ROTARY INTAGLIO PRINTING MACHINES

Application filed January 18, 1927, Serial No. 161,734, and in Germany January 21, 1926.

My invention relates to form cylinders for rotary intaglio printing machines and has particularly for its object, to devise an improved form cylinder of light metal for 5 instance of aluminum and a process of making same.

In the manufacture of such form cylinders it is very difficult to secure the copper coating, which serves as the etching ground, 10 immovably upon the light metal cylinder.

Also in case of said copper coating is electrolytically deposited upon the light metal cylinder, it will be very difficult to properly secure the copper coating upon the cylinder 15

25 in such a manner, that said coating will firmly adhere to said cylinder during operation.

According to the present invention, the electrolytically deposited copper coating is 20 firmly and inseparably connected with the light metal cylinder so that there will be no danger of the copper coating becoming loose during operation.

The form cylinder, according to this invention, is shown in the accompanying drawings, in which Figs. 1 and 2 are an elevation 25 of the new cylinder, while Figs. 3 to 5 are fragmentary sections through the cylinder.

The form cylinder *a*, as shown in Fig. 1 30 is provided with a groove, or thread, *b* of dove-tail cross-section, as may be seen from Fig. 3. A strap, ribbon or wire *c* of copper, or other well conducting metal, is placed into said groove, or thread, *b*, the cross-section 35 of said strap, ribbon or wire *c* being shown in Fig. 4. The inner surface of the copper strap *c* which bears on the bottom of the groove, or thread, *b*, as well as its outer surface are of arched conformation, 40 while its lateral edges are parallel with each other, so that the copper strap *c* may easily and conveniently be placed into the groove, or thread, *b*. After the strap, ribbon or wire *c* has thus been placed into the groove, 45 or thread, *b*, a strong pressure is exerted by means of a steel-roller, preferably with the aid of a lathe, upon the arched outer surface of the copper strap *c*. Thereby said arched outer surface will be depressed, and 50 the previously parallel lateral surfaces of

the copper strap *c* will be rolled into the groove, or thread, *b* of dove-tail conformation, as may be seen from Fig. 5. After said copper strap *c* has thus been rolled into said groove, or thread, *b*, the metal layer 55 *d* serving as the etching ground is placed upon the surface of the light metal cylinder. The metal layer, or copper coating *d* will thereby be firmly connected with the metal straps *c*, as shown in Fig. 5.

The grooves, or threads, *b* may also be provided upon the cylindrical surface of the form cylinder *a* parallel with the axis of the latter.

I claim:

1. A form cylinder for intaglio printing machines provided with a groove opening through the cylindrical surface of the cylinder, said groove being of greater cross sectional width inwardly of the cylindrical 70 surface of the cylinder than at said surface, a metal member disposed in said groove and conforming in cross sectional shape thereto, whereby said member is mechanically interlocked with the cylinder, and a metal coating electrolytically deposited on said cylinder and said member and electrolytically united with the latter.

2. A form cylinder for intaglio printing machines provided with a groove opening 80 through the cylindrical surface of the cylinder, said groove being of dovetail shape in cross section and of least width where it opens through the surface of the cylinder, a metal strip disposed in said groove and conforming in cross sectional shape thereto, whereby said strip is mechanically interlocked with the cylinder, the outer surface of said strip being disposed flush with the cylindrical surface of the cylinder and forming in effect a continuation of said cylindrical surface, and a metal coating electrolytically deposited on said cylinder and said strip and electrolytically united with the latter.

3. The method of providing an etching surface on a form cylinder for intaglio printing machines which consists in forming in the cylinder a groove opening through the cylindrical surface of the cylinder, form- 100

ing an inner portion of said groove of greater width than an outer portion thereof, placing a metal filler element in said groove, applying inward pressure against said filler element to expand the same into the portion of the groove of greatest width, thereby to mechanically interlock the filler element with the cylinder, and electrolytically depositing a coating of etching metal on said cylinder and said filler element.

4. The method of providing an etching surface on a form cylinder for intaglio printing machines which consists in forming in the cylinder a groove opening through the cylindrical surface of the cylinder, forming an inner portion of said groove of greater width than an outer portion thereof, providing a filler element for said groove having a cross section equal to the cross section of the groove and normally of a greatest width less than the least width of the groove, placing said filler element in the groove, applying inward pressure against said filler element to expand the same into the groove until the outer surface of the filler element forms in effect a flush continuation of the cylindrical surface of the cylinder, and electrolytically depositing a coating of etching metal on said cylinder and said filler element.

5. The method of providing an etching surface on a form cylinder for intaglio printing machines which consists in forming in the cylinder a groove opening through the cylindrical surface of the cylinder, laying a filler element of electrical conducting metal in said groove, applying inward pressure against said filler element to expand the same into firm engagement with the walls defining the groove, and electrolytically depositing a coating of etching metal on said cylinder and said filler element.

In testimony whereof I have affixed my signature.
